UNITED STATES PATENT OFFICE.

JOSEPH F. MUSSelman, OF BRONXVILLE, NEW YORK, AND PERRY WEST, OF NEWARK, NEW JERSEY, ASSIGNORS, BY MESNE ASSIGNMENTS, TO ELLIOTT COMPANY, OF PITTSBURGH, PENNSYLVANIA, A CORPORATION OF PENNSYLVANIA.

SYSTEM FOR RENDERING LIQUIDS NONCORROSION.

Application filed March 27, 1920. Serial No. 369,365.

This invention relates to a system for rendering water or other liquid non-corrosive and otherwise improving their character by the removal of the dissolved 5 oxygen and other corrosive gases or materials therefrom, thus rendering it corrosively inactive.

The object of this invention is to provide a simple, practical and efficient system in 10 which the active corrosive agents and other dissolved gases are more or less—and for all practical purposes completely removed from the liquid without raising the temperature of the same to the boiling point.

15 The invention consists in the novel arrangement and construction of the apparatus, as will appear more fully hereinafter in connection with the description of the 20 illustrative embodiment of the same shown in the accompanying drawings and particularly defined in the claims.

In the drawings we have shown, in conventional diagrammatical form, a typical arrangement or adaptation of our invention 25 to the hot water system of a building, the object being to prevent corrosion in the system of pipes through which water is delivered to the several parts of the building and also in the boiler for heating the water 30 supply.

The usual hot water system for a building is indicated by the tank 1, usually located on the roof, from which the water is supplied through the pipe line 2—3 to the heating tanks or boilers or other heating means 35 4—4, from which the several floors are supplied through the pipe 5 and risers 6, 7, and 8. The return pipe 9 carries the circulation 40 and surplus water back to the boilers or heating tanks 4—4.

The water thus supplied in the ordinary manner carries corrosive gases dissolved therein, such as oxygen and other free gases, carbonic acid gas and nitrogen, which, especially when the water is heated and in motion, are very active corrosive agents which destroy the pipes and boiler and also produce "gas pockets" and "slugs" in a closed hot water system, with resulting interferences 50 with the flow and circulation.

To accomplish these and other results, we provide a by-pass valve 10 in the supply line 2—3 which, when closed, causes the water to flow from the supply line 2 to a "weir box"

11, which is of the usual construction and 55 operation to maintain a constant rate of supply of water, which flows therefrom through a pipe 12 to a coil 13, the purpose of which will be explained hereinafter, and then through a coil 14 in an auxiliary heater 60 15 and through the pipe 16 to an inlet, preferably in the form of a spray device 17, to a chamber 18 in the upper part of a tank or container which is known as a "de-aerator" and the chamber 18 as a "de-aerating 65 chamber". This de-aerator is divided into upper and lower chambers by a perforated partition 19, the upper chamber 18 being the de-aerating chamber just described and the lower chamber 20 being known as an 70 "exchange chamber" and contains the coil 13 above referred to. The de-aerator is preferably located at a point sufficiently above the hot water system of pipes to the several floors to insure the flow of the water 75 thereto without the use of a pump.

From the chamber 20 the water passes through the pipes 21 and 22 to the supply pipe 3, on the opposite side of the valve 10, and thence through the hot water system 80 hereinbefore described.

The auxiliary heater 15, as shown, comprises an outer shell or casing which encloses the coil 14 and to which hot water or steam may be supplied and returned or circulated 85 through the pipes 23 and 24, controlled by a thermostatic valve 25; or other suitable heating means may be used which are adapted to heat the water passing into the de-aerator to a predetermined temperature 90 95 a few degrees below the boiling point.

The de-aerating chamber 18 is equipped with a series of pans 26 positioned under the inlet or spray device 17. These pans 26 are arranged to produce a "cascade" effect as 95 the water overflows from one to the other and a spray device 17, connected to the inlet end of the pipe 16 in the upper part of the chamber 18, may be used in connection with or instead of the pans, the object being to 100 agitate and separate the water into small particles and thus cause the corrosive gases to be given off.

A float 27 in the chamber 18 is operatively connected by means of a lever 28 and link 105 29 to a valve 30 in the supply line 12 and serves to regulate the level of the water in the chamber 18 of the de-aerator. A record-

ing thermometer or temperature gauge 32 may be provided to record the temperature of the water in the chamber 18 as a check on the operation of the auxiliary heater 15.

5 The de-aerated water fills the lower chamber 20, passing through the perforated wall 19, and surrounds the coil 13, giving off part of its heat thereto and heating the water passing therethrough to the auxiliary heater 15, thus reducing the amount of heating necessary to be done by the latter.

10 We have found by a number of experiments with our system that it is only necessary to heat the water entering the de-aerating chamber 18 to a point a few degrees under the boiling point and by the provision of the means for agitating and separating the water into small particles substantially all of the corrosive and other dissolved 15 gases are driven off and pass out through the vent pipe 31, located in the upper part of the de-aerating chamber 18.

15 The water after passing through the de-aerating chamber 18 is at a higher temperature than is required for ordinary use and a part of this heat is utilized in the exchange chamber 20 to heat the water passing through the coil 13, as above described, resulting in a greater economy in the operation 20 of the auxiliary heating means 14-15 and also permitting the use of a heating means of less capacity without reducing the efficiency of the system.

25 It will be obvious that our invention is adapted and useful for many purposes in addition to that described and shown in connection with the water supply of buildings, among which may be mentioned the making of "artificial" ice, in which the formation of "cores" and "opaqueness" is avoided when the water is treated in accordance with this invention before freezing. When used for this purpose the advantage of being able to deliver the water at 30 comparatively low temperature will be apparent.

35 Among many uses to which this system may be put may be mentioned the de-aerating of the water used in power plants and industrial plants for the prevention of corrosion in turbines, economizers, boilers, piping, etc. and the elimination of the objectionable rusty water in dye works, tanneries, bleacheries and other industrial processes.

40 In some cases the mechanical agitation of the liquid leaves a small percentage of dissolved gases therein and, as an auxiliary provision and to provide for the substantially complete removal of these gases, a corrosive or chemically active de-oxidizing or de-activating material or materials, such as iron, etc., may be used in the pans or in the de-activating tank, or in a separate tank, arranged to be brought into contact with the

45 liquid, preferably after it has been agitated, or while being agitated. This not only expedites the process of the removal of the gases from the liquid but, more particularly, insures the effectual removal of the remaining dissolved oxygen and other free corrosive gases from the liquid which remain after it has been subjected to the mechanical agitation process. This is especially useful where the volume of the liquid passing 50 through the de-activator is large for a given time.

55 As many changes could be made in the above construction and arrangement and many apparently widely different embodiments of our invention designed without departing from the scope and spirit of the invention as defined in the appended claims, we intend that all matter contained in the above description or shown in the accompanying drawings shall be interpreted as 60 illustrative merely of an operative embodiment of our invention and not in a limiting sense.

65 What we claim is:—

70 1. A system for rendering liquids non-corrosive, which comprises a deaerating tank having upper and lower communicating chambers, a series of pans positioned in said upper chamber to intercept the entering liquid and arranged to cause the same to flow successively from one pan to the next, means for heating the liquid before entering said tank to a temperature lower than the boiling point, said means including an auxiliary casing and heating coil therein, means for automatically maintaining the liquid in the heating coil at a predetermined 75 temperature, a coil positioned in said lower chamber in communication with the heating coil in the auxiliary chamber and surrounded by the heated liquid therein through which coil the liquid passes to the aforesaid heating means, and means for drawing off the liquid from said lower chamber of the tank.

80 2. A system for rendering liquids non-corrosive, which comprises a deaerating tank provided with means for agitating and separating the liquid supplied thereto into small particles, means including a heating casing for heating the liquid before entering said tank to a temperature lower than the boiling point, means for automatically controlling the temperature to which said means heats the liquid, means for utilizing the heat from the liquid in the tank to raise the temperature of the liquid passing into the aforesaid heating means, said means including communicating heating coils positioned in the tank and chamber, and means for drawing off the liquid from said tank after agitation.

85 3. A system for rendering liquids non-corrosive, which comprises a deaerating

5 tank provided with means for agitating and separating the liquid supplied thereto into small particles, means including a heating casing for heating the liquid before entering said tank to a temperature a few degrees below the boiling point, means for automatically controlling the temperature to which said means heats the liquid, means for utilizing the heat from the liquid in the 10 tank to raise the temperature of the liquid passing to the aforesaid heating means, said means including communicating heating coils positioned in the tank and chamber and means for drawing off the liquid from 15 said tank after agitation.

4. A system for rendering liquids non-corrosive, which comprises a deaerating tank having upper and lower communicating chambers, a series of pans positioned in 20 said upper chamber to intercept the entering liquid and arranged to cause the same to flow successively from one pan to the

next, heating means through which said liquid passes before entering said tank in which the liquid is heated to a temperature 25 lower than the normal boiling point, means connected with said heating means for automatically maintaining the liquid passing therethrough at a predetermined temperature, auxiliary heating means positioned in 30 said lower chamber of said tank adapted to conduct heat from the water in said lower chamber to the incoming water passing through said auxiliary heating means and connected to said first-mentioned heating 35 means and cooperating therewith for heating the liquid successively passing through said heating means to said upper chamber.

In testimony whereof, we the said JOSEPH F. MUSSELMAN and PERRY WEST, have 40 signed our names to this specification, this 10th day of March, 1920.

JOSEPH F. MUSSELMAN.
PERRY WEST.
